UNITED STATES PATENT OFFICE.

WILLIAM H. BEATTY, OF BIRMINGHAM, ALABAMA, ASSIGNOR TO BEATTY, PALMER AND BEATTY, A COPARTNERSHIP COMPOSED OF W. HENRY BEATTY, CLARENCE J. PALMER, AND WILLIAM H. BEATTY.

CENTRIFUGAL MOLDING APPARATUS.

Application filed August 24, 1927. Serial No. 215,066.

My invention relates to centrifugal molding machines and has for its object the provision of apparatus of the character designated which shall be simple and rugged in 5 its construction, and which shall embody means for readily mounting and removing the molding flask at the beginning and at the end of the molding operation.

My invention has more particular relation 10 to centrifugal molding machines employing a sand mold with a suitable flask therefor. In connection with such apparatus, the molds are first prepared in the flasks, away from the machine, and are then mounted on suitable 15 mechanism for rotating them while the molten metal is being poured and the casting formed. They are then taken away from the machine for the purpose of removing the casting while another flask and mold is put in 20 place for further pouring and casting. It will be obvious that with such apparatus, the machine should be so designed that the flasks may be readily mounted and removed from the machine, thereby reducing the time element and labor involved in the process. It is 25 accordingly the principal object of my invention to provide a machine for accomplishing the above mentioned purpose, and at the same time simplify the construction of such machines while producing a machine which shall 30 be as rugged or more rugged than machines already known to me.

Briefly, my invention comprises a pair of spaced pedestal members having provided 35 therein suitable bearings for a pair of idler rollers, one being positioned slightly above and to one side of the other, the idler rollers being so positioned that the flask, when in place, is only slightly to the 40 rear of the vertical central plane passing through the lower idler roller and lies entirely to one side of the other idler roller. A driven roller adapted to drive the flask by frictional engagement therewith, is so positioned 45 that its vertical central plane is on the same side of the axis of rotation of the flask as the lower idler roller. The driving roller has a shaft mounted in bearings carried by, and eccentrically disposed with respect to, 50 a bushing which, in turn, is mounted in suitable bearings in the spaced pedestals. A gear is carried by the bushing and meshes with a segmental gear having suitable operating means secured thereto and which is pivoted

on one of the pedestals. When the segmental gear is operated, it imparts a rotary motion 55 to the gear carried by the bushing, and the rotary motion of the bushing serves to raise or lower the shaft of the driving roller. A belt drive is provided for the driving roller 60 and is so positioned as to be tightened when the roller is lowered to engage with the flask.

Apparatus embodying features of my invention is illustrated in the accompanying drawing, forming a part of this application 65 wherein

Fig. 1 is a front elevation of the apparatus, with parts of the flask broken away;

Fig. 2 is a sectional view taken along the line II—II of Fig. 1; 70

Fig. 3 is an end elevation of the apparatus; and

Fig. 4 is a view in elevation of one of the idler rollers removed from the machine.

Referring to the drawing for a better understanding of my invention, I show, in Figs. 1 and 3, a base member 10 having mounted thereon a pair of spaced pedestals 11 and 12. A pair of idler rollers 13 and 14 each comprising two roller members, are disposed between the pedestals and have shafts 16 and 17 carried by suitable bearings in the pedestals. 75

A flask 18 containing a mold 19 may be mounted on the rollers 13 and 14. The roller 14, Fig. 4, is provided with flanges 15 which cooperate with runners 20, provided on the flask 18 to hold the latter in place. It will be noted that the rollers 13 and 14 are so positioned that the flask 18 rests on the upper 80 periphery of the roller 13 and only slightly to the rear of the central vertical plane thereof. The roller 14 is so positioned that the flask 18 rests entirely against the front side thereof, so that it acts as a stop for the 85 flask when putting it in place and holds it in such a position that it may be readily removed without lifting. At 21 is indicated a platform which may be of any suitable design and by means of which the flasks are rolled into place 90 in the machine and removed therefrom. 100

It will be apparent from the arrangement of the rollers, that a flask may be rolled into place for the operation of casting without danger or fear of displacement of the mold, 105 and after the molding operation is completed it may be readily removed from the machine with the expenditure of very little effort.

By this arrangement, I am enabled to greatly reduce the time required for casting as well as the effort required to place the flasks in position in the machine and remove them.

5 Arranged above the idler roller 13, and slightly forward of said roller, is a friction driving roller 22 adapted to rotate the flask 18 by frictional engagement therewith. The driving roller 22 comprises two roller members 10 constructed of suitable friction material, many forms of which will suggest themselves to those skilled in the art. For example, I have found what is known commercially as "friction paper" very satisfactory for this 15 purpose. The roller 22 is carried by a shaft 23 which is journaled in bearings 24 carried by a pair of similar bushings 26 and disposed eccentrically with respect to said bushings. The bushings 26 are in turn journaled in bearings 27 provided in the pedestals 11 and 12 so as to be freely rotatable in said bearings. 20 With this arrangement, upon rotation of the bushings 26, the shaft 23 may be raised and lowered and the roller 22 brought into or out 25 of frictional engagement with the flask 18. By placing the driving roller 22 slightly forward of the idler roller 13, it exerts a force, when in frictional engagement with the flask 18, tending to force the flask 18 toward the 30 roller 14 and thus holds the flask firmly in place between the idler rollers.

Each of the bushings 26 is provided with a gear 28 arranged on the outer end thereof. The gears 28 mesh with segmental gears 29 35 carried by a shaft 31 journaled in bearings 32, the latter being carried by the pedestals 11 and 12. Secured to the shaft 31 is a lever 33 which coacts with a quadrant 34 carried by the pedestal 12. The lever 33 is provided 40 with a latch 36 which engages the teeth of the quadrant to hold the segmental gear 29 in any desired position and consequently determines the position of the shaft 23 and the driving roller 22. The shaft 23 is prefer- 45 ably driven in a counter clock-wise direction as viewed in Fig. 3, by a rope belt 37 the latter being driven from any suitable source, not shown, and which is preferably arranged in a position above the shaft 23. The reason for 50 driving the roller 22 in a counter clock-wise direction is to cause the flask 18 to bear more tightly against the idler roller 14 in rotation. By so arranging the belt 37, it will be obvious 55 that upon raising the roller 22, the belt is slackened and upon lowering said roller the belt is tightened.

The upward movement which may be transmitted to the shaft 23 by the segmental gear 29 and the gear 28 is sufficient to permit 60 the mounting of a flask in position in the machine for the molding operation and to remove the flask therefrom. When the flask 18 is in position, as shown in Fig. 1 of the drawing, molten metal is introduced into the 65 mold as by means of a spout 38 which, as is

well understood in the art, may be entered into the open end of the mold and retracted therefrom as the molding operation is carried out. While the molten metal is being poured, the roller 22 is held in frictional engagement 70 with the flask and the flask is rapidly rotated. As soon as the molten metal has been poured the lever 33 is moved upward, as viewed in the drawing, raising the shaft 23 and rollers 22 free of the flask. Thus, the imparting of ro- 75 tary movement to the flask 18 and the freeing of the flask so that it may be readily removed is accomplished by one movement of the lever 33. When this has been done, the flask 18 may be readily removed from the machine 80 and disposed of in any desired manner known to the art.

From the foregoing it will be apparent that I have devised an improved centrifugal molding machine wherein the molding flasks may 85 be readily placed in position and removed therefrom, and wherein means are provided for disengaging the flask and stopping the motion thereof in one operation.

While I have shown my invention in but 90 one form, it will be obvious to those skilled in the art that it is not so limited, but is susceptible of various changes and modifications, without departing from the spirit thereof, 95 and I desire, therefore, that only such limitations shall be placed thereupon as are imposed by the prior art or as are specifically set forth in the appended claims.

What I claim is:

1. In a centrifugal molding machine, a 100 pair of idler rollers for supporting a flask, a driving roller, means for imparting rotary movement through the driving roller to the flask, and means for raising and lowering the driving roller to permit the mounting and re- 105 moval of the flask from said supporting rollers.

2. In a centrifugal molding machine, a pair 110 of idler rollers for supporting a flask, said rollers being so disposed that the flask rests upon the upper periphery of one of the idler rollers and entirely to one side of the other idler roller, a driving roller for rotating the flask, a shaft for the driving roller, means for transmitting rotary movement to the shaft, 115 and means for moving the shaft to disengage the driving roller from the flask to permit the mounting and removal of said flask from the machine.

3. In a centrifugal molding machine, a 120 flask, a lower supporting roller, a lateral sup- 125 porting roller so positioned as to maintain the flask on the upper periphery of the lower roller, a driving roller arranged above the flask and adapted to drive said flask by frictional engagement therewith, and means for raising and lowering the driving roller.

4. In a centrifugal molding machine, a flask, a lower supporting roller, a lateral sup- 130 porting roller so positioned as to maintain

- the flask on the upper periphery of the lower roller, a driving roller arranged above the flask and adapted to drive said flask by frictional engagement therewith, means for raising and lowering the driving roller to free it from and engage it with the flask, a belt drive for the driving roller and so disposed that upon engagement of the roller with the flask the belt is tightened.
- 5 5. In a centrifugal molding machine, a pair of spaced pedestals, a pair of idler rollers having shafts, bearings for the shafts provided in the pedestals and so disposed that the flask when mounted on the rollers lies slightly to one side of the vertical plane passing through the center of one of the rollers and entirely to one side of the other roller, a driving roller adapted to rotate the flask by frictional engagement therewith, bushings carried by the pedestal members above the idler roller, a shaft for the driving roller, bearings for the last mentioned shaft mounted in the bushings and eccentric thereto, gear means for rotating the bushings, and means for operating the gear means, whereby the driving shaft and its roller are raised or lowered by reason of rotation of the bushings.
- 10 6. In a centrifugal molding machine, a flask, a pair of idler rollers, said rollers being so positioned that the flask when in place for molding rests on the upper periphery of one of the rollers, a driving roller disposed above the flask and adapted to rotate said flask by frictional engagement therewith, a shaft for the driving roller, bearings for the shaft, a pair of bushings for supporting the bearings, said bearings being eccentric to the bushings,
- 15 gear means carried by the bushings, a segmental gear meshing with the gear means and manually operable means for operating the segmental gears.
- 20 7. In a centrifugal molding machine, a flask, a lower flask supporting idler roller, a lateral flask supporting idler roller disposed to the rear of the lower roller so that the flask when in position in the machine rests on the upper periphery of the lower roller with its long axis slightly to the rear of the long axis of the lower roller, a friction driving roller adapted to frictionally engage the flask and disposed above the flask with its long axis forward of the long axis of the lower roller, and means to raise and lower the driving roller to permit the mounting and removal of the flask.
- 25 8. In a centrifugal molding machine, a flask, a lower flask supporting idler roller, a lateral flask supporting idler roller disposed to the rear of the lower roller so that the flask when in position in the machine rests on the upper periphery of the lower roller with its long axis slightly to the rear of the long axis of the lower roller, a friction driving roller adapted to frictionally engage the flask and disposed above the flask with its long axis forward of the long axis of the lower roller, means to raise and lower the driving roller to permit the mounting and removal of the flask, and means to drive the friction roller in a direction to force the flask over against the lateral idler roller.
- 30 65
- 35 60
- 40 65
- 45 70
- 50 55
- 55
5. In testimony whereof I affix my signature.
- WILLIAM H. BEATTY.
